UNITED STATES PATENT OFFICE.

CHARLES S. BAVIER, OF NEW YORK, N. Y.

APPARATUS FOR COOLING AND UTILIZING AIR.

No. 907,559.

Specification of Letters Patent.

Patented Dec. 22, 1908.

Application filed May 21, 1906. Serial No. 318,057.

To all whom it may concern:

Be it known that I, CHARLES S. BAVIER, of New York, in the State of New York, have invented certain new and useful Improvements in Apparatus for Cooling and Utilizing Air; and I do hereby declare the following to be a full, clear, and exact description of the invention, such as will enable others skilled in the art to which it appertains to make and use the same.

The object of this invention is the provision of means for utilizing waste or exhaust air, having special reference to ventilation exhaust, that is the foul or vitiated air expelled from a room or compartment to the atmosphere and replaced by atmospheric air under natural conditions or after being cooled or purified. This may be termed an open system or circuit by reason of being in communication with the atmosphere at its inlet and exhaust, in contradistinction to the closed systems or circuits which re-chill and circulate the same air in a confined space.

The primary application of the invention is to those ventilating systems employing refrigerating media, with the view to effecting a saving in their operating cost and an increase in efficiency. The means to that end is the utilization of the flow, volume, and low temperature of the exhaust air with its resident capacity to absorb the higher compression temperatures of gas liquefaction.

I have found that exhaust or vitiated air flowing from ventilating systems may be utilized to materially aid condensing-evaporative and water-cooling processes in effecting such condensation and cooling by absorbing the higher temperatures of such evaporative surfaces and the heated vapors in water cooling towers; and is also available in effecting the condensation of refrigerant gases by absorbing the higher surface temperatures of the condenser and the humidity surrounding such surfaces. This is especially true of the air issuing from a room ventilated by artificial means because this air necessarily flows rapidly through the system of pipes or flues so that considerable absorbing properties reside in the exhaust which may be availed of by utilizing the system of its circulation before it is finally discharged into the atmosphere. I have also found that exhaust or vitiated air when at a temperature lower than that of the atmospheric air may constitute a primary absorber for the heat

of the incoming draft of air at atmospheric temperature when the paths of the two are arranged in proximity.

In the accompanying drawing I have indicated diagrammatically a ventilating and cooling system embodying the principle of my invention.

Referring to the drawing, 1 designates an air cooler and 2 a condenser. 2^a is a gas receiver in communication with the condenser and cooler and 2^b and 2^c are pipes leading from a still or compressor (not shown) to the condenser and cooler, respectively. It will be understood that these elements, or the refrigerating plant of which they are part, do not enter into my invention and that they may be of any preferred construction, it being assumed, however, that in the cooling room an evaporating agent, such as ammonia gas, is expanded, and that in the condenser 2 this gas is reliquefied. The pipe 3 conducts the atmospheric air to the cooler and through pipe 4 the cooled air is transmitted to the room or compartment 5, the exit from which is indicated at 6.

7 is the exhaust flue which I have shown leading from room 5 into one end of the gas condenser room 2, the discharge outlet 8 from the condenser room being shown at the other end thereof.

In the exhaust flue 7 I have shown a casing or housing 9 having a series of tubes 10 communicating with the flue. The inlet pipe 3 through which atmospheric air is entrained opens into housing 9 so that the air when passing in through the pipe is retarded for a while in the enlarged area afforded by the housing and circulates about the tubes 10 before continuing through pipe 3 to the cooling room.

12 indicates a by-pass by which passage through flue 7 may be maintained independently of housing 9, valves 13 controlling the line of direction.

In the condenser room 2 water is sprayed over the coils and the gases enter at 14 and leave at 15.

Suitable fans and other features of construction, forming no part of this invention, may of course be employed.

In use, assuming the system to be employed in the summer season when the temperature to be maintained in room 5 is considerably less than that of the outside air, it follows that the exhaust from the room pass-

ing through tubes 10 is cooler than the air entering through duct 3 and consequently as this outside air circulates about tubes 10 in the housing part of its heat units are given 5 up to the exhaust air within the tubes. Thus the incoming air conducted to the cooling room from the primary heat absorber 9 will be lessened in temperature when it reaches the cooler, while the exhaust after leaving 10 the tubes 10 is increased in temperature correspondingly by the time it enters the condensing room. When the conditions are such that the temperature maintained in room 5 is equal to or higher than that of the 15 atmosphere the exhaust is directed through by-pass 12 to the gas condenser. But under any conditions it is available for use in this condenser where its lowest temperature (as it issues from flue 7) acts upon the coolest 20 portion of the condenser coils which is adjacent the outlet. The air and cooling water exert their combined absorbing capacity upon the heated surface. As the capacity for absorption and evaporation depends 25 upon the extremes of heat and humidity between the absorbing agents and the surfaces on which they act it will be apparent that the air will be saturated by the time it leaves the condenser room through the terminal out- 30 let 8.

It will be obvious to those skilled in the art that by my invention the operating cost of an artificial cooling system is lessened and the efficiency materially enhanced. It will 35 also be apparent that the exhaust or vitiated air may also be availed of for steam condensation, whether with the customary water-cooling tower or by the evaporative condenser system.

I claim as my invention:

1. In a ventilating system open to the atmosphere at its initial point and at its termination and having a compartment to be ventilated, a gas expansion cooling system comprising a cooling room having a coil therein 45 for the expansion of the gases, and a condenser to effect their liquefaction connected to the said coil, a passage from said cooling room to said compartment, and a passage from said compartment to said condenser, 50 whereby the flow and heat absorbing capacity of the exhaust air from said compartment are utilized in the liquefaction of the gases.

2. In a ventilating system, a compartment 55 to be ventilated, a gas expansion cooling system comprising a cooling room having a coil therein for the expansion of the gases, a condenser to effect their liquefaction connected to the said coil, means for conducting atmospheric air to said cooling room, and a heat absorber in the path of the atmospheric air, a passage from said cooling room to said compartment, a passage from said compartment to said heat absorber, and a passage from 60 said heat absorber to said condenser, whereby the flow and heat absorbing capacity of the exhaust air from said compartment are utilized to partially absorb the heat of the atmospheric air in said absorber and to assist in liquefying the gases in said condenser. 65

In testimony whereof, I have signed this specification in the presence of two subscribing witnesses.

CHARLES S. BAVIER.
